GARMENT HANGER ATTACHMENT

Michael F. Smith, Los Angeles, Calif.

Application July 23, 1945, Serial No. 606,579

6 Claims. (Cl. 223—93)

1

My invention relates to an attachment mountable upon a conventional garment hanger to aid in keeping in place certain garments supportable by the hanger.

Among important objects of the invention are: to provide an attachment or clip adapted to be applied adjustably to a garment hanger and including means for maintaining the holding means of the device either in a clamped closed or unclamped open relation to an arm of the hanger; to provide in combination with the attachment a boot or sleeve, preferably elastic, to provide in combination with the attachment a boot or sleeve, preferably of an elastic character to afford: first, a protective covering for the tiltable portion of the attachment; secondly, a gripping action to contract the yieldable wire frame of the attachment whereby to frictionally hold the latter on the hanger bar when a certain link is optionally omitted; and finally to serve as a non-slip means to prevent the slipping off of silky or satiny garments from the hanger bar when such garments are superimposed upon shoulder strap garments supported on the bar by the attachment thereunderneath; to provide a garment hanger clip more satisfactorily operable by a single hand of the operator leaving the other hand free to adjust garments on the hanger; and to provide an adjustable keeper clip of a flat line character that will not distort overlying garments.

Other objects, advantages and features of invention will hereinafter appear.

Referring to the accompanying drawing which illustrates what is at present deemed to be a preferred embodiment of the invention,

Fig. 1 is a perspective view of the device the keeper sleeve which may form a part thereof being shown juxtaposed to the part to which it is applied.

Fig. 2 is a side elevation of a garment hanger showing each arm of the hanger provided with the device, one of the two devices shown being in the open position and the other in the closed position.

Referring in detail to the drawing, the conventional hanger therein shown, comprises an arcuate bar or body portion 5 suspendable by a wire hook 6 attached to its midlength portion.

Mountable upon each end portion of said hanger is the adjustable clip 7 which forms the subject matter of this invention. Said clip 7 comprises a resilient wire frame consisting of two approximately parallel basal wire runs 8 said runs at one end each being continued as an upward vertical run 9 which in turn is continued

2

by a forward approximately horizontal run 10 at each side of the clip, said runs 10 also being approximately parallel to the lower or basal runs 8. The upper runs 10 are slightly dipped downwardly throughout their front portions, their forward ends being united by a transverse front wire run 11, while the rear portions of said runs 10 are linked together by a link member 12 which is shown as a piece of strap metal having end curls 13 securing it to said wire runs 10.

Each of the basal or lower wire runs 8 has its front end portion 14 directed steeply downward and terminating in an eye portion 15 whereby this part of the clip is attached to a headed pin or rivet 16. Said pin 16 forms a pivotal support for a cam member or dog 17 shaped as a triangular block, the pin passing through one rounded corner portion or heel of said block.

One face 18 of said block is shown concave so as to be more conveniently engaged by the thumb of the operator to operate it, while the adjoining face 19 at the opposite side of the pivot is slightly convex so that in one adjusted position of the dog the latter face will abut squarely against the concave side of the hanger 5, as shown in the right hand portion of Fig. 2. The third face 20 of the dog is also slightly convex to conform to the contour of the lower side of the hanger.

The upper wire portions 10 and 11 together with the strap metal link 12 of the clip constitute an upper stirrup shaped abutment member 21 (Fig. 2) which overlies the upper surface of the hanger arm when the clip is in the applied position. Said member 21 being so positioned in relation to the pivot pin 16 and the triangular dog 17 that when the dog is adjusted with its face 19 abutting against the hanger bar said member 21 is maintained upwardly tilted as shown in the right hand portion of Fig. 2, and when said dog is adjusted with its face 20 in an abutting relation to the hanger bar said member 21 is held downwardly in an overlying abutting relation to the upper surface of the hanger bar, as shown in the left hand portion of Fig. 2. The vertical wire runs 9 of the attachment are held closely against opposite sides of the hanger bar by means of the link 12, thereby frictionally holding the member 21 in its upwardly tilted position when so desired; it being understood that in imparting an anti-clockwise movement to the dog 17 to bring it to the position in the right hand portion of Fig. 2 the wire portion 21 of the device will be thrown upward to its tilted position. The frictional engagement of the wire runs 9 will also

yieldingly maintain the attachment in its adjusted position in relation to the length of the hanger bar 5.

With the member 21 of the attachment upwardly tilted as just stated the shoulder strap of a suspended garment may be inserted under said member 21 (at each end of the hanger bar) and then the clip adjusted so as to bring the members 21 down snugly upon the shoulder straps of shoulder-strap garments. When the clips are thus adjusted other garments may be hung upon the hanger in the usual way without being distorted by the smooth underlying members 21.

When the dog 17 has been brought to the position shown at the left in Fig. 2, wherein its face 20 abuts the lower side of the hanger bar, the wire portion of the clip as a whole is placed under tension which causes its part 21 to firmly grip and hold in place the aforementioned underlying shoulder straps.

An antislip sleeve 25, preferably made of rubber-like material, is provided for each attachment to envelop the overlying wire member 21. The runs 10 of each member 21 diverge slightly from each other as they approach the wire run 11 and the sleeve 25 tapers slightly to its mouth position so that when said sleeve is telescoped over the wire member 21 it will safely stay in place.

When the sleeve 25 is made a part of the device and is in the applied position, if desired, the strap metal link 12 may be omitted, because the mouth portion of the sleeve will function the same as the link when used.

It should be understood that the present disclosure is for the purpose of illustration only and that this invention includes all modifications and equivalents which fall within the scope of the subject matter claimed.

What is claimed is:

1. A garment hanger attachment of the kind described comprising a resilient wire frame consisting of two approximately parallel basal runs, said runs at one end each being continued as an upward vertical run which in turn is continued by a forward approximately horizontal upper run at each side of the attachment, the latter runs also being approximately parallel to said lower or basal runs, said upper runs being slightly dipped downwardly throughout their front portions, their forward ends being united by a transverse front wire run, a link linking together the rear portions of the latter runs, each of said basal or lower runs of the wire frame having its front end portion directed steeply downwardly and terminating in an eye, a pin bridging the space between said eyes, and a triangularly shaped dog having one of its corner portions pivotally related to said pin whereby said dog is adjustable to bring one of its faces into an abutting relation to a hanger bar to which the attachment is applicable, allowing when so adjusted an upward tilting of said upper wire runs in relation to the hanger bar and when adjusted with another of its faces abutting said hanger bar draws said upper wire runs downwardly yieldingly against the upper surface of the hanger bar.

2. A garment hanger attachment of the kind described comprising an upper member consisting of a resilient wire loop bent like a U to horizontally overlie and abut a longitudinal section of the top surface of a conventional garment hanger bar, a wire run depending downwardly from each arm of said member, a link linking

together the arms of the U adjacent to the point where said wire runs depend therefrom to cause the latter runs to frictionally grip between them the hanger bar, and means to underlie the hanger bar and unite the lower ends of said wire runs, said attachment being adjustable to and from a position wherein said member is upwardly tilted at one end to admit under it a shoulder strap of a garment to be supported by the hanger.

3. A garment hanger attachment of the kind described comprising an upper resilient wire loop formed at one end and having side portions positionable along opposite upper corner portions of a conventional garment hanger bar, an elastic sleeve enveloping said wire loop, the mouth of said sleeve being contracted and fitting around that end of the loop opposite its said closed end, said loop having a downwardly extending run located at each side of the mouth of the fitted on sleeve, said downwardly extending runs gripping between them the hanger bar, means to underlie the hanger bar and unite the lower ends of said wire runs, said attachment being adjustable to and from a position wherein said wire loop and sleeve are upwardly tilted at one end to admit under the sleeve the shoulder strap of a garment supported by the hanger, and means to effect the adjustability of said attachment, said means including a dog pivoted to said underlying means and adjustable to and from a position wherein it acts against the underside of the hanger bar when the device is in the applied position to at such time cause said upper portion of the wire frame to press down upon the upper surface of the hanger bar and grip therebetween said shoulder strap.

4. An attachment for a conventional garment hanger, comprising a resilient wire frame having an upper portion to overlie the bar of the hanger, side portions to grip between them the bar of the hanger, and a lower portion to underlie the bar of the hanger, in combination with a cam member or dog pivoted to said lower portion and adjustable to and from a position wherein it acts against the underside of the hanger bar when the device is in the applied position to at such time cause said upper portion of the wire frame to press down upon the upper surface of the hanger bar.

5. The subject matter of claim 4 and, said cam member or dog being shaped with one of its corner portions pivotally related to said wire frame, whereby when adjusted with one of its faces in an abutting relation to the hanger bar it allows an upward tilting of the wire frame in relation to the hanger bar and when adjusted with another of its faces in abutment with the hanger bar, draws the upper portion of the wire frame downwardly yieldingly against the upper surface of the hanger bar.

6. A clip for application to that type of garment hanger which consists of a bar suspendable from its central portion in a horizontal position; consisting of an upper abutment member in an abutting, tiltable relation to the upper side of said bar, a lower portion in an underlying spaced relation to said upper portion and rigidly secured to one end of the latter portion, and a dog pivotally mounted upon said underlying portion to adjust said latter portion to and from a down-clamped relation to the upper surface of the hanger bar.

MICHAEL F. SMITH.
